United States Patent Office.

JOHN LOADER, OF LONDON, ENGLAND, ASSIGNOR TO HIMSELF, WILLIAM HENRY CHILD, AND AARON WHITE COOK WILLIAMS, OF SAME PLACE.

Letters Patent No. 103,901, dated June 7, 1870.

IMPROVEMENT IN PACKING FOR ROTARY ENGINES.

The Schedule referred to in these Letters Patent and making part of the same.

I, JOHN LOADER, of London, England, engineer, have invented certain "Improvements in Rotary Engines," of which the following is a specification.

This invention relates to the novel construction of certain parts of a rotary engine, which may also be used for pumping and measuring liquids.

Description of the Drawing.

Figure 1 is a front elevation of my improved engine, with the cylinder-cover removed.

Figure 2 is a vertical section on the line $x x$, fig. 1.

Like letters indicate the same parts in both of the figures.

My improved engine has a central shaft or axis, a , on which is formed or fixed a crank, b , or eccentric.

The shaft a passes through the cylinder c , which has a long neck, e' , provided with a stuffing-box and gland.

On the crank-pin b' , or eccentric, is mounted a disk, d , which forms the piston, and which is so moved as to keep a portion of its periphery in contact with the inner periphery of the cylinder.

The piston does not revolve upon its axis, but, as the said axis revolves, the piston gyrates in a peculiar manner therewith, and at the same time rocks to and fro on the joint e , which slides up and down on the stop or abutment f .

The said stop or abutment f is, by preference, rigidly fixed in the cylinder, as shown, and it passes through the two parts $e^1 e^2$ of the cylindrical joint e , which works in a correspondingly formed recess within the disk or piston d , a suitable opening, g , being formed within the disk or piston to admit the end of the said stop or abutment as the disk or piston is moved to and fro by the crank-pin or eccentric on which it is mounted.

The joint is provided with a packing-plate, f^3 , which is kept in contact with the surface of the abutment by a small spring, f^4 , and insures the joint being kept perfectly tight.

The disk or piston d is provided with a number of packing-pieces, h , which are received into suitable undercut recesses formed across the periphery of the disk or piston, and are caused to bear with an elastic pressure upon the interior of the periphery of the cylinder by springs i .

The sides of the piston may be kept steam-tight by means of a disk or plate placed between the piston and cylinder, but this additional plate will not usually

be required, as it is sufficient to make the piston fit properly between the back of the cylinder and the cover j . I prefer to form a narrow piece or ring, a^x , around the face of the cylinder, to facilitate the fitting of the parts together.

The steam or other motive fluid is admitted at one side of the stop or abutment, while the exhaust-port is on the other side of the said abutment. If it is desired to work the steam or other fluid expansively, I cause the steam to enter at the side of the stop or abutment, as shown, by a passage therein, which communicates with the steam-pipe outside the cylinder.

The inlet-port k must be formed in such a position that it will be closed at a suitable time before the outlet-port e^3 is opened.

If it is desired to make the engine reversible, I provide the cylinder with an inlet and outlet-port on each side of the abutment, and furnish them with valves or cocks, whereby each set of valves may be opened or closed as desired.

Two, or any other desired number of these cylinders and pistons may be connected with one shaft. When only one cylinder is used, I provide the shaft with a fly-wheel, n .

It is obvious that, by very slight modifications of this invention, the same may also be employed as a rotary pump or water-meter.

I am aware that many of the parts herein described have been before known in rotary engines and pumps, but they have failed of full success for want of other parts, or of a proper construction and arrangement. I do not claim any of the features, except as hereinafter enumerated.

I claim—

1. The internal bearing-piece f^3 and spring f^4 , arranged as represented, relatively to the cheeks $e^1 e^2$, abutment f , piston d , and its inclosing casing and passages, for the purposes herein set forth.

2. The combination of the packing-pieces h , and their operating means, piston d , gyrating as described, cheeks $e^1 e^2$, contained piece f^3 , and spring f^4 , all arranged for joint operation relatively to each other and to the abutment f and casing c , as herein specified.

JOHN LOADER. [L. S.]
